GAME BOARD

Humbert Robertson, 965 Tinton Ave.,
Bronx, N.Y. 10456

Filed Sept. 23, 1965, Ser. No. 87,145

Term of patent 14 years

(Cl. D34—5)

Fig. 1

FIG.
2FIG.
3

The figures are shown fragmentarily in portions for convenience of illustration.

The dominant features of the design reside in the full line portions shown.

I claim:

The ornamental design for a game board, as shown and described.
